UNITED STATES PATENT OFFICE.

WILLIAM H. LIMBERG, OF PLYMOUTH, WISCONSIN.

MOULD FOR MAKING SOLID CONCRETE SILOS.

No. 857,474.

Specification of Letters Patent.

Patented June 18, 1907.

Application filed April 6, 1907. Serial No. 366,773.

To all whom it may concern:

Be it known that I, WILLIAM H. LIMBERG, a citizen of the United States, residing at Plymouth, in the county of Sheboygan and State of Wisconsin, have invented a new and useful Mold for Making Solid Concrete Silos, of which the following is a specification.

This invention relates to molds for making silos and similar structures from cement, concrete and other plastic material and has for its object to provide a strong durable mold of this character by means of which artificial stone silos may be quickly and conveniently manufactured.

15 A further object of the invention is to provide a sectional mold capable of being readily set up for use and quickly knocked down and compactly assembled for transportation or shipment.

20 A further object is to provide means for locking the adjacent mold sections in engagement with each other and means for preventing lateral displacement of said sections.

25 A further object is to provide a plurality of spaced tie-rods for reinforcing and strengthening the silo and further to form the interior walls of the silo with a longitudinally disposed seating recess for the reception of the doors of the silo.

30 A still further object of the invention is to generally improve this class of molds so as to increase their utility, durability and efficiency.

35 Further objects and advantages will appear in the following description, it being understood that various changes in form, proportions and minor details of construction may be resorted to within the scope of the appended claims.

40 In the accompanying drawings forming a part of this specification: Figure 1 is a top plan view of a sectional mold constructed in accordance with my invention. Fig. 2 is a side elevation showing the several mold sections secured together and disposed in superposed order. Fig. 3 is a detail vertical sectional view. Fig. 4 is a vertical sectional view taken on the line 4-4 of Fig. 1, and looking in the direction of the arrow.

45 50 Similar numerals of reference indicate corresponding parts in all of the figures of the drawings.

The improved mold forming the subject matter of the present invention includes an outer shell member 5 and an inner shell member 6, said members being spaced apart to

form an intermediate chamber adapted to receive the cement, concrete or other plastic material, indicated at 7.

The inner and outer shell members 5 and 6 are preferably constructed of galvanized iron or other suitable material and are each preferably formed of a plurality of sections of segments 8 having their opposite ends reinforced and strengthened by vertically disposed angle bars 9 which may be riveted, bolted or otherwise rigidly secured to the sections, as shown. The lateral flanges of the angle bars 9 are provided with aligned perforations for the reception of suitable connecting bolts 10 whereby the several sections may be securely fastened together when the mold is set up for use and readily detached and compactly assembled for transportation or shipment. The opposite longitudinal edges of each section 8 are also reinforced by longitudinal angle bars 11 preferably curved to conform to the shape of the sections 8 and terminating flush with the adjacent vertical edge of the angle bars 9 so as to prevent the sections 8 from spreading or buckling when the cement is introduced into the molding compartment.

As a means for alining the several sections when the mold is set up for use the lower longitudinal flange 11 of each section is provided with a depending integral lug 12 preferably formed by slitting the metal, as indicated at 13, said lug 12 being adapted to enter a correspondingly shaped recess 14 formed in the upper reinforcing bar of an adjacent section whereby said sections are effectually locked against lateral displacement.

The adjacent longitudinal edges of the inner and outer shell members 5 and 6 are spaced apart at 15' and seated between the walls of the shell members at said opening are longitudinal timbers each preferably formed in two sections 15 and 16 and which serve to close the adjacent ends of the molding compartment. The sections 15 of the longitudinal timbers are preferably off-set and provided with inclined faces 17 adapted to form a correspondingly shaped seating recess in the interior walls of the silo for the reception of the sectional doors or closures of the latter.

As a means for reinforcing and strengthening the walls of the silo suitable tie-rods or bars 18 are preferably embedded in the cement during the formation of the silo, said bars being provided with angularly disposed

anchoring members 19 and constituting a ladder so that access may be readily obtained through the doors or closures to any particular portion of the silo.

5. The sections 15 and 16 of the longitudinal timbers are preferably formed with segmental recesses or sockets 20 adapted to accommodate the tie-rods 18, said longitudinal timbers being retained in position between 10 the side walls of the shell members 5 and 6 by means of suitable clamping bolts 21 which also extend through the timbers, as shown.

In using the mold the angle bars of adjacent sections are secured together by the 15 bolts 10 after which the sections are arranged one above the other in superposed order with the vertical angle bars 10 of one section disposed in staggered relation to or arranged to break joint with the vertical angle bars of 20 the next succeeding section and with the locking lugs 12 seated in the adjacent sockets 14 thus securely locking the several sections in assembled position. The longitudinal timbers are then interposed between 25 the shell sections and secured by the clamping bolts 21 after which the cement, concrete or other plastic material is shoveled or otherwise introduced into the molding compartment and thoroughly tamped. In order to 30 remove the mold it is merely necessary to detach the lugs 12 from the sockets 14 and subsequently remove the bolts 10 when the mold sections may be readily detached from the silo.

35. By having the inner and outer shell members formed in sections the same may be readily adjusted so as to make silos of different cross sectional diameter and said sections may be compactly folded for transportation 40 or shipment.

From the foregoing description it will be seen that there is provided an extremely simple, inexpensive and efficient device admirably adapted for the attainment of the 45 ends in view.

Having thus described the invention what is claimed is:

1. A mold including inner and outer shell members, spaced apart to form an intermediate molding chamber and each formed of a plurality of sections provided with marginal reinforcing flanges, the metal forming one of the flanges of each section being provided with spaced incisions and the metal between 55 said incisions bent downwardly to form a depending lug adapted to engage a recess formed in the flange of an adjacent section, for locking said sections in superposed order.

2. A mold including inner and outer shell 60 members spaced apart to form an intermediate molding compartment and each formed

of a plurality of sections having their adjacent ends detachably secured together, longitudinal timbers seated between said members and spaced inwardly from the adjacent 65 ends thereof, and clamping bolts extending transversely through the timbers and adjacent shell members for locking said timbers within the molding compartment.

3. A mold including inner and outer shell 70 members spaced apart to form a molding compartment and each formed of a plurality of sections having their adjacent ends detachably connected, longitudinal timbers interposed between the walls of the shell 75 members and spaced inwardly from the adjacent ends thereof, said timbers being provided with lateral off-sets having their ends inclined or beveled, and clamping members extending through the walls of the shell 80 members and timbers, respectively for locking the latter within the molding compartment.

4. A mold including inner and outer shell 85 members spaced apart to form an intermediate molding compartment, sectional longitudinal timbers interposed between the walls of the shell members, clamping bolts extending through the shell members and timbers, respectively, for locking the latter within the 90 molding compartment, tie-rods extending transversely through the timbers and having their opposite ends disposed within the molding compartment, there being recesses formed in the edges of the longitudinal timbers for 95 the reception of the tie-rods.

5. A mold including inner and outer shell members spaced apart to form an intermediate molding compartment and each formed of a plurality of segmental sections having their adjacent ends reinforced by perforated angle bars, fastening devices passing through the perforations of adjacent angle bars for securing the sections in assembled position, angle bars secured to the upper and lower 100 edges of the several sections and curved to conform to the curvature of said sections, there being a recess formed in one of the longitudinal angle bars of each section, and integral lugs depending from the opposite 105 angle bar of each section and adapted to enter the contiguous recess in the longitudinal angle bar of an adjacent section thereby to lock said sections against accidental displacement.

In testimony that I claim the foregoing as my own, I have hereto affixed my signature in the presence of two witnesses.

WILLIAM H. LIMBERG.
